UNITED STATES PATENT OFFICE

ALFRED WILLIAM BENNIS, OF BOLTON, ENGLAND

TURBULENT BURNER

Application filed March 29, 1929, Serial No. 350,984, and in Great Britain April 2, 1928.

The present invention relates to turbulent burners particularly for pulverulent fuels.

In the known types of turbulent burners the mixing of the finely divided fuel and air has been accomplished by whirling about the fuel and the air either combined or separately, and either with a low or a high velocity. The action therefore, has been chiefly whirling as distinct from a turbulent motion such as is caused when liquid is poured from a vessel into a tumbler or the like from a great height.

In these known types of burners, inclined vanes have been used to obtain the necessary whirling effect, but it will be appreciated that greater mixing of the fuel and air is desired beyond that which can be accomplished by any whirling action. The greater the proportion of air which can be introduced into the finely divided fuel and the more intimate the mixing between such air and the fuel, the more rapid and efficient will be the subsequent combustion.

According to the present invention the streams of air and fuel are passed into the burner and have their direction of travel violently reversed as distinct from being given a whirling action, with the result that turbulence is set up and the fuel particles are caused to fly violently amongst and intermingle with the molecules of air.

By reversal of direction is meant a change of direction greater than 90° the maximum reversal of course being when the change of direction is equal to 180° .

Preferably the burner is provided with a base portion against which the fuel and air is projected and after turbulence has been set up, the resultant mixture is projected through a suitable orifice into the furnace. The burner is preferably of a cup or tumbler-like form, the exit orifice of the burner being of any desired shape according to the desired shape of flame.

One or more annular or other orifices or channels may be provided around the burner through which additional hot or cold air required for combustion may be supplied. These annular orifices or channels around

the orifice of the burner may be adjustably controlled.

The base of the burner may be adjusted from the outside of the furnace so as to alter the relationship of the fuel feeding orifices and the base thereby adjusting the turbulent effect.

The invention is more particularly described with reference to the accompanying drawings in which:—

Figure 1 shows in section one form of turbulent burner constructed according to the present invention.

Figure 2 is a cross sectional view of Figure 1 on the line 2, 2 of Figure 1.

Figure 3 is a section of a modified form of construction.

Figure 4 is a cross sectional elevation along the line 6, 6 of Figure 3.

Figure 5 is a sectional view of another form of construction.

Figure 6 is a cross sectional view thereof along the line 11, 11 of Figure 5.

Figure 7 is a sectional elevation of a still further modified form of construction of burner.

In the drawings, which are provided to illustrate certain examples of construction of the invention and are not intended to confine the invention to the examples illustrated, and with regard to Figures 1 and 2 in particular the burner is formed in three portions 12, 13 and 14 connected together by flanges, the inlet for the pulverulent fuel and air being indicated at 15 and being formed in the portion 12, whilst the portion 13 forms the body part of the burner and the portion 14 the mouth piece thereof. It will be understood that instead of air any suitable form of gas may be used, and this term is used solely as a descriptive term and not as a limiting term throughout the description and claims.

The base member of the burner is indicated at 16. This base member is mounted for longitudinal movement in the burner. A spindle 17 is rigidly connected to the base member and extends through the wall of the burner where it has a threaded connection with the bracket so that when a suitable tool

is applied to the end 18 of the spindle, it may be turned for shifting the position of the base burner. By this means the position of the reaction plate or base member 16 of the burner may be shifted relative to the inner wall 19 forming the chamber of the burner.

The mixing chamber, within which turbulence of the combustible medium takes place, is provided with a number of inlet orifices 20 at the ends of inlet passages 21, these passages 21 communicating with a space 22 through passages 23 within which inclined or angled ribs or vanes 26 are formed. 10 15 The inclined ribs or vanes 26 create a swirling or centrifugal effect on the air or gas and fuel passing through the ducts 23.

The cross sectional area of the passages 21 slightly decreases from one end to the other in order to prevent trapping of the fuel and air or gas during their passage therethrough, this decrease of the cross sectional area being necessary in view of the fact that the inlet for the fuel and air from 20 25 these passages into the chamber 24 of the burner is not at right angles to the direction of the passages.

It will be seen from this construction that one inlet only is provided both for the supply of the fuel and air.

When the air and fuel enter the burner through the orifice 15, a certain amount of initial turbulence is set up by reason of the projecting end 25 of the base member which 30 35 lies in the path of the flow of the incoming air and fuel. The air and fuel then flow along passages 23 and 21 and the orifice 20 into the mixing chamber 24. By reason of the shape of the chamber 22 it is possible that 40 45 a bigger proportion of fuel will be present in the medium passing along the lower passages 23 than along the higher passages 23 by reason of the action of the centrifugal force on the air and fuel, but this has no effect on the resultant mixture of fuel and air as the most efficient mixing takes place when the fuel and air enter the chamber 24 and impinges against the base plate 16 prior to its complete reversal of direction of travel 50 55 outwardly through the mouth piece 14.

The burner shown in Figures 3 and 4 is basically the same as shown in Figures 1 and 2 with certain added features of structure. In this construction an inlet 37 is provided 60 65 for the primary air and fuel, whilst a separate inlet 38 is provided for the secondary air. The passage of the primary air and fuel along ducts 39 between a plurality of angled or inclined ribs or vanes 40 formed therein has a suction effect on the secondary air to cause this to enter the ducts 21 and from thence through the orifices 20 into the burner chamber 24. The primary air of course, is 70 75 that volume of air sufficient to convey the powdered fuel into the burner chamber and

is generally somewhere in the region of 30% of the total air supply.

In this case by reason of the suction effect of the primary air on the secondary air, the hot secondary air from the furnace can be 70 75 used.

In this construction a modified piece 61 is provided within which propeller shaped blades or vanes are mounted on a shaft 64 which is supported within bearings 65 controlled by a remote control 66 situated externally of the burner.

The remaining details with regard to the construction of Figures 3 and 4 are similar to the construction described with reference 80 to Figures 1 and 2.

In Figures 5 and 6 of the drawings, a further modified form of burner is shown. In this form of the burner, the same basic principles of the burner illustrated in Figures 1 and 2 are used, with the added feature of the sleeve 55 which is disposed between the inner wall 19 of the burner and the base or reaction piece 16. The sleeve 55 is mounted so that it is shiftable. A tubular member 56 is connected to the sleeve and extends through the rear wall of the burner and has a threaded connection with a bracket, so that by turning the tubular member, the sleeve is adjusted. The spindle 17 attached to the 90 95 base or reaction piece 16 extends through this tubular member 56 and beyond the end thereof, and the end 18 is shaped so that it may be turned, thus providing a remote control for positioning the base or reaction piece 100 105 110 115 120 125 130 135 140 145 150 155 160 165 170 175 180 185 190 195 200 205 210 215 220 225 230 235 240 245 250 255 260 265 270 with a bracket and a manually operable member 70 for turning the tubular member for adjusting the sleeve. There is also present in this construction a plurality of vanes 63 mounted on a rod 64. The rod 64 is mounted in bearings and extends through a sleeve 67 and is provided with a remote control 66 therefor whereby it may be turned. This feature of construction is shown and described 10 more in detail in connection with Figure 1.

In addition to these features which have been described in connection with Figures 1 to 6, there is a secondary air supply. Surrounding the mouth piece 61 of the burner 15 is a casing having ports 58 controlled by dampers 59 which may be independently or collectively operated. The primary air passes in with the fuel through an inlet 60. Secondary air is drawn through these ports 20 and is discharged in an annular whirling sheet into the air and fuel mixture leaving the burner mouth. The whirling of the air is accomplished by means of inclined or angular ribs or vanes 58^a similar to those described in connection with Figures 1 and 2.

It will be appreciated that in the constructions according to the drawings the air and fuel is efficiently mixed prior to ignition by the turbulence set up in the burner chamber 30 due to the violent reversal of direction of flow of the fuel and air or gas in such chamber. A certain amount of mixing, however, does take place before the chamber is reached by reason of the action of centrifugal force 35 on the fuel and air or gas due to the angled ribs or vanes situated in the ducts between the inlet ports to the burner for the fuel and air or gas and the inlet ports to the burner chamber.

40 The base or reaction piece in each case preferably has a conical surface against which the air and fuel are projected, such conical surface causing a greater reversal of direction for the mixture to be projected outwardly from the burner, in view of the fact that the inlet orifices are situated in the walls of the burner chamber, than would be the case where the base or reaction piece has a plane surface at right angles to the walls of 45 the burner chamber.

I declare that what I claim is:—

1. A burner for pulverulent material having an opening at the outlet end thereof forming the mouth of the burner, a mixing chamber in rear of and opening into said burner mouth, said burner having an inlet passage for the fuel and air mixture adjacent the inlet end of the burner, and an annular 55 passage leading from said inlet passage longitudinally of and around the mixing chamber to a position in front of the rear of the mixing chamber and thence inwardly in substantially a reversed direction into said mixing chamber, whereby a turbulence is set up 60

in the flowing mixture and a complete mixing of the fuel and air effected.

2. A burner for pulverulent material having an opening at the outlet end thereof forming the mouth of the burner, a mixing chamber in rear of and opening into said burner mouth, said burner having an inlet passage for the fuel and air mixture adjacent the inlet end of the burner, and an annular passage leading from said inlet passage longitudinally of and around the mixing chamber to a position in front of the rear of the mixing chamber and thence inwardly in substantially a reversed direction into said mixing chamber, whereby a turbulence is set up in the flowing mixture and a complete mixing of the fuel and air effected, the rear wall of the mixing chamber being mounted so that it may be adjusted axially of the burner, and means accessible from the outside of the burner for adjusting said wall. 75

3. A burner for pulverulent material having an opening at the outlet end thereof forming the mouth of the burner, a mixing chamber in rear of and opening into said burner mouth, said burner having an inlet passage for the fuel and air mixture adjacent the inlet end of the burner, and an annular passage leading from said inlet passage longitudinally of and around the mixing chamber to a position in front of the rear of the mixing chamber and thence inwardly in substantially a reversed direction into said mixing chamber, whereby a turbulence is set up in the flowing mixture and a complete mixing of the fuel and air effected, the rear wall of the mixing chamber being mounted so that it may be adjusted axially of the burner, and means accessible from the outside of the burner for adjusting said wall. 80

4. A burner for pulverulent material having an opening at the outlet end thereof forming the mouth of the burner, a mixing chamber in rear of and opening into said burner mouth, said burner having an inlet passage for the fuel and air mixture adjacent the inlet end of the burner, and an annular passage leading from said inlet passage longitudinally of and around the mixing chamber to a position in front of the rear of the mixing chamber and thence inwardly in substantially a reversed direction into said mixing chamber, whereby a turbulence is set up in the flowing mixture and a complete mixing of the fuel and air effected, a cylindrical sleeve surrounding the rear portion of the mixing chamber and shiftable axially of the burner for regulating the size of the inlet passage leading into said mixing chamber, and means accessible from the outside of the burner for shifting said sleeve. 85

5. A burner for pulverulent material having an opening at the outlet end thereof forming the mouth of the burner, a mixing chamber in rear of and opening into said burner mouth, said burner having an inlet passage for the fuel and air mixture adjacent the inlet end of the burner, and an annular passage leading from said inlet passage longitudinally of and around the mixing chamber to a position in front of the rear of the mixing chamber and thence inwardly in substantially a reversed direction into said mixing chamber, whereby a turbulence is set up in the flowing mixture and a complete mixing of the fuel and air effected, a cylindrical sleeve surrounding the rear portion of the mixing chamber and shiftable axially of the burner for regulating the size of the inlet passage leading into said mixing chamber, and means accessible from the outside of the burner for shifting said sleeve. 90

6. A burner for pulverulent material having an opening at the outlet end thereof forming the mouth of the burner, a mixing chamber in rear of and opening into said burner mouth, said burner having an inlet passage for the fuel and air mixture adjacent the inlet end of the burner, and an annular passage leading from said inlet passage longitudinally of and around the mixing chamber to a position in front of the rear of the mixing chamber and thence inwardly in substantially a reversed direction into said mixing chamber, whereby a turbulence is set up in the flowing mixture and a complete mixing of the fuel and air effected, a cylindrical sleeve surrounding the rear portion of the mixing chamber and shiftable axially of the burner for regulating the size of the inlet passage leading into said mixing chamber, and means accessible from the outside of the burner for shifting said sleeve, the rear wall of the mixing chamber being mounted for adjustment, and means accessible from the outside of the burner for shifting said sleeve. 95

sible from the outside of the burner for shifting said wall.

5. A burner for pulverulent material having an opening at the outlet end thereof forming the mouth of the burner, a mixing chamber in rear of and opening into said burner mouth, said burner having an inlet passage for the fuel and air mixture adjacent the inlet end of the burner, and an annular passage leading from said inlet passage longitudinally of and around the mixing chamber to a position in front of the rear of the mixing chamber and thence inwardly in substantially a reversed direction 70 into said mixing chamber, whereby a turbulence is set up in the flowing mixture and a complete mixing of the fuel and air effected, said annular passage for the fuel and air being provided with ribs disposed at an angle 75 to the longitudinal axis of the burner whereby the mixture contacting with said ribs will be given a swirling motion prior to the entering of the mixing chamber.

6. A burner for pulverulent material having an opening at the outlet end thereof forming the mouth of the burner, a mixing chamber in rear of and opening into said burner mouth, said burner having an inlet passage for the fuel and air mixture adjacent the inlet end of the burner, and an annular passage leading from said inlet passages longitudinally of and around the mixing chamber to a position in front of the rear of the mixing chamber and thence inwardly in substantially a reversed direction 80 into said mixing chamber, whereby a turbulence is set up in the flowing mixture and a complete mixing of the fuel and air effected, said annular passage throughout a portion 85 of its length being parallel to the axis of the burner and immediately adjacent the inwardly extending passages leading to the mixing chamber divergent away from said chamber.

7. A burner for pulverulent material having an opening at the outlet end thereof forming the mouth of the burner, a mixing chamber in rear of and opening into said burner mouth, said burner having an inlet passage for the fuel and air mixture adjacent the inlet end of the burner, and an annular passage leading from said inlet passage longitudinally of and around the mixing chamber to a position in front of the rear of the mixing chamber and thence inwardly in substantially a reversed direction 90 into said mixing chamber, whereby a turbulence is set up in the flowing mixture and a complete mixing of the fuel and air effected, said burner having secondary means for supplying air to the mixture of fuel and air as it leaves the burner, and means for controlling the secondary supply of air.

8. A burner for pulverulent material having an opening at the outlet end thereof

forming the mouth of the burner, a mixing chamber in rear of and opening into said burner mouth, said burner having an inlet passage for the fuel and air mixture adjacent the inlet end of the burner, and an annular passage leading from said inlet passage longitudinally of and around the mixing chamber to a position in front of the rear of the mixing chamber and thence inwardly in substantially a reversed direction 75 into said mixing chamber, whereby a turbulence is set up in the flowing mixture and a complete mixing of the fuel and air effected, and displaceable vanes mounted in the mouth of said burner and means accessible from the outside of the burner for shifting the position of said vanes.

In witness whereof, I have hereunto signed my name this 12th day of March, 1929.

ALFRED WILLIAM BENNIS. 85
